UNITED STATES PATENT OFFICE.

CHRISTIAN G. FILZER, OF ERIE, PENNSYLVANIA.

HYDROCARBON-TORCH.

1,274,403.

Specification of Letters Patent. Patented Aug. 6, 1918.

Application filed January 24, 1918. Serial No. 213,481.

To all whom it may concern:

Be it known that I, CHRISTIAN G. FILZER, a citizen of the United States, residing at Erie, in the county of Erie and State of Pennsylvania, have invented certain new and useful Improvements in Hydrocarbon-Torches; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to hydro-carbon torches of the type shown and described in my prior Letters-Patent Nos. 1,204,967 and 1,204,968, issued November 14, 1916, and consists in certain improvements in filter mechanism and hinged connection mechanism hereinafter particularly described and pointed out and illustrated in the accompanying drawings, in which:

Figure 1 is a side elevation of a hydro-carbon torch embodying my invention.

Fig. 2 is a plan view of a fragment thereof showing the spring suspension of the hinged connection.

Fig. 3 is an enlarged horizontal central section of the same.

Fig. 4 is a side elevation of a portion of the same looking in the direction of the arrow in Fig. 3.

Fig. 5 is an enlarged vertical central section of a fragment of the torch mechanism.

Fig. 6 is an enlarged side view of my improved vapor filter tube.

Fig. 7 is an enlarged cross section of the same through one of the filter openings in the wall thereof.

In these drawings A, indicates the liquid fuel container, A', indicates an air pump by means of which the desired pressure is maintained in the container; B, indicates the

needle-valve housing which communicates with the container; B' indicates the vapor generator; b, indicates the tube leading into the generator; b' indicates the tube leading from the generator; C, indicates the return

bend connection leading to the vapor jet-tube C', all of said parts being of ordinary construction as shown and described in my above mentioned patents.

Connected to the housing B is a tube D which leads into a tube D' at right angles thereto (see Fig. 3) from which a tube d

extends at right angles to the tube D', and parallel with the tube D, terminating in a short tube E which is at right angles to the tube d', and parallel with the tube D'. 60

The interior of the tube E is chambered out, as shown at e in said Fig. 3. Abutting

against the open end of the tube E is a tube F', the axis of which is in alinement with the axis of the tube E. The tube F is pro-

vided with an annular collar which projects into the chamber e and forms a journal bearing for the tube F' to rotate upon. The tube F' is chambered out as shown at f' in

Fig. 3, and from the tube F' a tube F ex- 70

extends at right angles to the axis of the chamber f', and will swing in the plane of the axis of the tube D. Within the duct e

and chamber f' there is a bolt G which fits an opening f² leading into the chamber f' 75

and is provided with threads g which en- gage the threads in the opening f² and is

adapted to hold the tube F in place in the tube E. Upon the screw-threaded end of

the bolt G I place a jam-nut G' which 80

prevents the bolt G from turning on the threads in the opening f². The tube F is

also provided with a stud F² in which one end of a coiled spring H which is wound around the extension F' is secured, the other 85

end of said spring engaging the tube D' as

shown. From the foregoing it will be seen that the tube F is transversely hinged or 90

pivoted upon the tube E and swings within the plane of the axis of the tube D. To

permit liquid fuel to flow through the ducts d, d', and f, I provide a clearance at the

opening f³ into the chamber f' preferably by cutting a flat surface g' on the bolt G, 95

as shown in Figs. 3 and 4. This however may be accomplished in any other suitable manner. The clearance thus provided should not be greater than the diameter of the jet-opening in the jet-tube hereinafter described, so that the fluid passing there- 100

through will be strained and any particles of solid matter which may be in the liquid fuel which will not pass through said jet opening will not pass through said clearance space. Secured in the duct f of the 105

tube F is the tube c of the return-bend connection C (see Fig. 5) with which tube c the tube b of the generator is connected in the usual manner. Upon the tube c is sup- 110

ported the vapor jet-tube C' having a fine jet-opening c' in the front end thereon, the interior thereof being enlarged sufficiently

to receive the inner end of the filter-tube J and support it concentric with the wall of the counter-bored chamber c^2 in said jet-tube C'. The rear end of the jet-tube C' 5 is closed by means of a screw plug K which has a central opening k extending from the inner end of said plug into the head portion thereof to receive and support the rear end of said filter-tube J, so that when said screw-plug K is removed from the jet-tube C' the rear end of the filter-tube will project slightly from the rear end of the jet-tube C' so that said filter-tube can be easily removed therefrom. The opening in the 10 screw-plug K is preferably sufficiently greater in diameter than the filter-tube J that there is a small clearance in said opening around the filter-tube to permit vapor to pass therethrough to the rear end of said filter tube and yet will prevent any particles of solid matter from passing therethrough. The filter tube J is provided with small openings j through the walls thereof of a size designed to prevent particles of 15 solid matter large enough to clog the jet opening c' from passing therethrough. In making the filter-tube J a piece of tube is cut to the desired length and then I make transverse saw-cuts therein as shown in Figs. 6 and 7, of sufficient depth so that the 20 metal is of a thinness substantially like paper, and then by means of a suitable instrument openings j are pricked through such paper-thin metal, as it is difficult to otherwise make the openings j small enough. In the rear end of the filter tube J there is also 25 preferably cut a small slot, or slots j' through which vapor may flow into the tube J. From the generator tube b' a duct 30 c^3 leads through the return bend connection to the counter-bored chamber c^2 in the jet-tube C'.

In operation the bolt G is screwed up tight enough so that the spring H will not 45 cause the tube F and generator B' secured thereto to swing upward, and then the jam-nut G' is tightened sufficiently to prevent said bolt from becoming loosened, when the generator B' can be manually swung upward or downward without readjusting the bolt G, and the spring H will support the generator in the required position. If it were not for the action of the spring H the bolt G would have to be adjusted so tightly 50 to maintain the generator in the position required that it could not be moved without loosening the bolt.

When the needle-valve in the housing P is 60 opened liquid fuel flows through the ducts d , d' , and e in the hinged connection illustrated in Figs. 2 and 3, and is filtered through the clearance space g' in the opening f' which prevents particles of solid matter therein from passing into the duct f and 65 thence into the generator with the liquid

fuel. From the duct f the liquid fuel flows through the generator tube b into the generator B' wherein it is transformed into vapor in the usual manner and said vapor flows back through the tube b' and duct c^3 70 (see Fig. 5) into the chamber c^2 in the jet-tube C', and thence through the filter openings j, into the filter-tube J, and thence to the jet-opening c'. I am thus enabled to filter the fuel both before and after vaporization, so that by means of my improvements there is practically no possibility of the jet-opening c' becoming clogged during the operation of the torch. 75

Having thus shown and described my invention so that others can utilize the same, what I claim and desire to secure is:

1. In a hydro-carbon torch, a container, a valve housing in communication therewith, a vapor generator, a transversely hinged tubular connection between said housing and said generator, a cylindrical projection in axial alinement with the pivot of said hinged connection, and a spring coiled around said projection one end thereof engaging the movable member of said connection and the opposite end thereof engaging the stationary member of said connection, substantially as set forth. 80
2. In a hydro-carbon torch a fluid fuel container, a valve housing communicating therewith, a vapor generator, a vapor jet-tube in communication with said generator, a vapor filter in said jet-tube, a hinged connection between said generator and said valve housing, and fluid fuel straining means in said hinged connection, substantially as set forth. 85
3. In a hinged connection for the fuel supply duct of hydro-carbon torches, a right-angle duct, a swinging duct abutting against the end of said right-angle duct, and a bolt passing through said right-angle duct and transversely through said swinging duct member having a flattened surface thereon to permit the flow of liquid fuel from said right-angle duct into said swinging duct member, substantially as set forth. 90
4. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 95
5. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 100
6. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 105
7. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 110
8. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 115
9. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 120
10. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 125
11. In a hinged connection for the fuel supply duct of hydro-carbon torches, a right-angle duct communicating with said supply duct, a swinging tubular member, an annular flange on the side thereof adapted to enter said right-angle duct, an annular shoulder around said flange adapted to abut against the end of said right-angle duct, a chamber in said swinging duct member, a projection on said swinging duct member opposite said annular shoulder having a screw-threaded opening therethrough in axial alinement with said collar and annular shoulder, a pivot bolt having a flat surface on the side thereof passing through said right-angle duct, said chamber and engaging said screw-threaded opening, and a 130

jam-nut on said bolt, substantially as set forth.

5. In a vapor filter for hydro-carbon torches, a vapor jet-tube having a jet opening in one end thereof, a concentric tube therein communicating with said jet opening and having filter slots in the rear end thereof, and a screw plug to close the rear

end of said jet-tube and being provided with a longitudinal opening therein adapted to 10 receive the rear end of said concentric tube and permit vapor to pass to said slots in the rear end of said concentric tube, substantially as set forth.

In testimony whereof I affix my signature.
CHRISTIAN G. FILZER.
